Inventor:
William E. Wegener,
By Dyerforth, Lee, Crittenden & Miles,
Attest:

UNITED STATES PATENT OFFICE.

WILLIAM E. WEGENER, OF CHICAGO HEIGHTS, ILLINOIS.

SHEET-GRIPPER.

1,343,537.

Specification of Letters Patent. Patented June 15, 1920.

Application filed February 26, 1920. Serial No. 361,454.

To all whom it may concern:

Be it known that I, WILLIAM E. WEGENER, a citizen of the United States, residing at Chicago Heights, in the county of Cook and State of Illinois, have invented a new and useful Improvement in Sheet-Grippers, of which the following is a specification.

My invention relates more particularly to sheet grippers for use in the manipulation of sheets of paper and cardboard, and more particularly the positioning of sheets of paper and cardboard on a support for receiving impressions, as in the case of printing machines, the device having been devised for use more particularly, though not to the exclusion of its use in other situations, in connection with what is known as a Miller platen press feeder, my improved device being provided as the fork portion of such a machine.

In the machine of the type referred to the paper gripper is provided in a position to receive the forward edge of the sheet in the delivery operation of the machine, the sheet being delivered against stops which are engaged by such forward edge, and by a shifting movement given to the fork forming the gripper, the sheet is moved laterally against another stop on the machine by which stops the sheet is accurately positioned on the platen, the gripper in such movement moving away from and out of engagement with the sheet and being returned to normal position to again receive the edge of a sheet, after the previously positioned sheet has received the desired impression and been removed from the platen.

It will be understood from the foregoing that the sheet gripper must be so constructed that while it will receive the edge of a sheet delivered to it in the operation of the machine, it will afford sufficient resistance to the withdrawal of the sheet therefrom to effect the desired shifting of the sheet, by the action of the gripper described, for positioning the sheet against the lateral stop as stated.

In this connection, it is my object to provide a novel, simple and economical construction of gripper by which the same may be readily adjusted to cause it to function as stated for different thicknesses of sheets with which it is to be used.

Referring to the accompanying drawing, Figure 1 is a broken plan view of the fork 55 of a Miller platen press - feeder, equipped with sheet - gripping means in accordance with my invention. Fig. 2 is a bottom plan view of the structure shown in Fig. 1. Fig. 3 is a plan view of the structure of Fig. 1 60 with certain of the parts shown in Fig. 2 removed. Fig. 4 is an enlarged section taken at the line 4 on Fig. 1 and viewed in the direction of the arrow. Fig. 5 is a section taken at the line 5 on Fig. 1 and viewed in 65 the direction of the arrow; and Fig. 6, a view in side elevation of the device of Fig. 1, Figs. 1, 2, 3 and 6 showing the structure considerably enlarged compared with the size of the same for use on the Miller machine 70 referred to.

The part indicated at 7, and which is preferably formed of a piece of spring steel, is the part at which the feed-gripper is attached to the Miller machine referred to and 75 through which the lateral oscillations of the gripper device, in the operation of the machine, are effected, this strip being formed at its outer end with a tongue 8, its relatively pointed end being beveled and 80 rounded at its upper side as indicated at 9. The tongue portion 8 is narrower than the body of the strip 7 and presents at the base of the tongue the outwardly-extending shoulders 10. Fitting flatwise against the 85 upper surface of the strip 7 is a plate 11 preferably of springy material, as for example brass, having its outer end expanded as indicated at 12 and its extremity of fork shape providing the tines, or tongues, 13 90 which are spaced apart and extend at opposite sides of the tongue 8 and in spaced relation thereto, the metal of the part 12 at the bases of the tines or tongues 13, at opposite sides of the tongue 8, being downwardly deflected as represented at 14' to form lugs which interlock with the shoulders 10 as shown. The fork portion of the member 11 normally inclines slightly in a direction away from the plane in which the tongue 8 100 is located, the extremities of the tines 13 being upwardly curved as indicated in Fig. 6, viz., in a direction away from the tongue 8. The members 7 and 11, related to each other as shown and explained, are associated with 105 a block 14 which is of increased thickness at

its rear end as indicated at 15 and in which part a longitudinally extending dove-tail groove 15^a is provided, in which groove the assembled members 7 and 11 are contained 5 and adjustable lengthwise, a set screw 16 in the block 14 and screwing against the member 11 serving to hold the parts 7, 11 and 14 in adjusted position. The forward end of the block 14, and which is of reduced thickness as represented at 17, is recessed as indicated at 18, to provide the two forwardly-projecting arm portions 19 spaced apart a distance substantially equal to the distance between the tines 13, directly above which latter they extend. The under sides of the portions 19 are upwardly curved as indicated at 20, the parts 19 carrying adjusting screws 21 which bear against the upper surfaces of the tines 13 and through the medium of 10 which these tines may be adjusted into different positions for the purpose hereinafter explained.

In the use of the device the sheets of paper, or cardboard, one being indicated at 22, 25 are fed in succession to the device, one at a time, the forward edge of the sheet entering the gripper and engaging stops (not shown) at its forward edge, the sheet becoming superposed on the tongue 8 and 30 extending beneath the tongues 13 which latter are, through the medium of the screws 21, adjusted relative to the tongue 8 to permit the sheet to become positioned in the gripper as shown and stated but held by 35 the gripper with sufficient firmness to cause the sheet to be shifted laterally for the positioning purpose stated in the forepart of this specification, and the gripper is thereupon withdrawn from engagement with the 40 sheet, when the gripper is oscillated in a lateral direction.

The functioning of the gripper as stated depends upon the position of the tongues 13 relative to the tongue 8 and the characteristics and thickness of the sheet being 45 operated on, it being possible by my improved device merely by the making of a simple adjustment, as through the medium of the screws 21, to condition the gripper 50 device for the performance of the functions above referred to, in connection with sheets of varying characteristics and thicknesses.

Furthermore by reason of the construction as shown the tongues between which the sheet is gripped, when once adjusted, 55 are maintained, in the continued use of the device, in the position to which they are adjusted, such relative positioning of the tongues not being disturbed by continued 60 use of the device.

While I have illustrated and described a particular construction embodying my invention, I do not wish to be understood as intending to limit it thereto, as the same 65 may be variously modified and altered with-

out departing from the spirit of my invention.

What I claim as new and desire to secure by Letters Patent is:

1. A sheet gripper comprising members 76 constructed and arranged to permit a sheet to be entered edgewise therebetween and become automatically gripped therein by the act of thus inserting the sheet, and means for relatively adjusting said members to 78 adapt the device for use with sheets of different thicknesses.

2. A sheet gripper comprising members 80 by which the sheet is engaged, certain of said members being spaced apart and another thereof located between said spaced apart members, and means for relatively adjusting said members to adapt the device for use with sheets of different thicknesses.

3. A sheet gripper comprising a block, 85 members carried by said block and by which the sheet is engaged, and means on said block for relatively adjusting said members to adapt the device for use with sheets of different thicknesses. 90

4. A sheet gripper comprising a block, members on said block and by which the sheet is engaged, certain of said members being spaced apart and another thereof located between said spaced apart members, and 95 means on said block for relatively adjusting said members to adapt the device for use with sheets of different thicknesses.

5. A sheet gripper comprising a block, 10 members on said block by which the sheet is engaged, certain of said members being spaced apart and another thereof located between said spaced apart members, and adjusting means carried by said block and engaging said spaced apart members for 10 adjusting the latter relative to the said member between them, to adapt the device for use with sheets of different thicknesses.

6. A sheet gripper comprising a block, 11 members on said block by which the sheet is engaged, certain of said members being resilient, and means on said block engaging said last-referred-to members for adjusting the latter relative to the other of said members. 11

7. A sheet gripper comprising a block, a tongue member on said block, and a plate provided at its forward end with resilient members spaced apart and located at opposite sides of said tongue and in position to 120 adapt the device to receive a sheet between said tongue and members, and means on said block for adjusting said spaced apart members toward and away from said tongue.

8. A sheet gripper comprising a block 125 formed at its forward end with arms spaced apart, a tongue equipped member carried by said block and extending at its tongue between said arms, said member being shouldered at the base of said tongue, a 130

yoke-shape member carried by said block and located between said tongue-equipped member and said block and formed with tongues at its forward end spaced apart and located at opposite sides of said first named tongue, said second-referred-to tongues being resilient, and set screws car-

ried by said arms and bearing against said resilient tongues and through the medium of which screws, said resilient tongues are 10 adjustable relative to said first-referred-to tongue.

WILLIAM E. WEGENER.
